UNITED STATES PATENT OFFICE.

FRANK A. HAUGH, OF INDEPENDENCE, KANSAS.

UNDERREAMER.

1,137,615.

Specification of Letters Patent. Patented Apr. 27, 1915.

Application filed April 21, 1914. Serial No. 833,467.

To all whom it may concern:

Be it known that I, FRANK A. HAUGH, a citizen of the United States, residing at Independence, in the county of Montgomery 5 and State of Kansas, have invented new and useful Improvements in Underreamers, of which the following is a specification.

This invention relates to under-reamers for use in sinking well casings, the primary 10 object being to provide a tool of this character which includes a body having a plurality of expansible and detachable cutters connected therewith, together with means by which the cutters may be maintained in 15 collapsed, unobstructing position while passing through the casing, but which will expand the cutters so as to render the same operative as soon as the reamer has emerged from the lower end of the casing.

20 A further object of the invention is to provide a tool of the class described wherein the means for expanding the cutters is adapted to secure the same rigidly in their operative positions, but is adapted to be rendered 25 inoperative by an actuating device which engages the lower end of the casing as the reamer enters the same in being withdrawn after the cutting operation has been completed.

30 A still further object is the provision of an under-reamer whose parts are simply constructed and few in number so as to be capable of being assembled or detached readily for the purpose of repair, and whereby 35 the tool is rendered extremely durable and also inexpensive in the cost of manufacture.

The invention consists in the features of construction, combination, and arrangement of parts, hereinafter fully described 40 and claimed, reference being had to the accompanying drawings, in which:

Figure 1 is a side elevation of the tool showing the cutters and the plunger inoperative while the device is passing through a 45 well casing; Fig. 2 is a similar view showing the cutters and the plunger in their operative positions, the casing being omitted; Fig. 3 is a front elevation of the same; Fig. 4 is a bottom plan view; Fig. 5 is a longitudinal 50 sectional view on line 5—5 of Fig. 1; Fig. 6 is a similar view on line 6—6 of Fig. 3; Fig. 7 is a transverse sectional view on line 7—7 of Fig. 5; and, Fig. 8 is a detail perspective view of one of the cutters.

In the drawings, the numeral 1 designates 55 the cylindrical body of the tool which is provided in its lower end with a socket 2 in which a cylindrical supporting member 3 is adapted to be mounted and to be secured therein by means of a transverse pin 4, which latter is adapted to extend through an opening 5 in the body 1 and a registering groove 6 in the supporting member, the lower end of the socket 2 is enlarged as at 7 and an annular groove 8 is provided in the socket 65 adjacent to the said end. The bottom wall 9 of the groove 8 is cut at a forty-five degree angle to the longitudinal axis of the body whereas the upper wall thereof is frusto-conical in shape, it being inclined to the 70 said axis. A plurality of cutters 10, each of which is substantially segmental in transverse section, have their upper ends reduced as at 11 for reception within the socket 75 groove 8 of the body, these reduced portions being shaped externally the same as the said groove so as to fit snugly therein when in their expanded, operative positions, wherein their shoulders 12 abut the marginal portion of the lower end of the body. The 80 reduced portions 11 of the cutters are thus provided above the shoulders 12 with opposed shoulders 13 for engagement with the bottom wall 9 of the groove 8. The upper 85 ends of the cutters are provided with radially disposed openings 14 for the reception of the supporting pins 15 which project outwardly from the reduced lower end 16 of the supporting member 3. These pins are loosely engaged within the said openings so 90 as to permit slight swinging movement of the cutters in expanding and collapsing.

The body 1 is provided in communication with its socket 2 with an upwardly projecting central bore 17, and the supporting 95 member 3 is provided with a medial bore 18 in registration therewith, for the reception of a longitudinally movable plunger 19 whose lower end is adapted to project through the space provided between the cutters. The inner faces of the cutters adjacent to the upper ends thereof are longitudinally inclined as at 20 so as to converge upwardly and they are adapted to be engaged by a frusto-conical enlargement 21 which is formed upon the outer periphery of the plunger 19 in spaced relation to its lower end, this enlargement being adapted 100 105

to expand the upper ends of the cutters so that they will fit securely within the socket groove 8, when the plunger is moved upwardly. The lower end portions of the inner faces of the cutters are inclined more abruptly and are adapted for engagement by a second expanding and reinforcing head 22, which latter is constructed frusto-conical in shape like the enlargement 21, but 10 greater in mean diameter than the same. Upwardly tapering spacing lugs 23 are formed upon the outer periphery of the expanding head 22 for engagement between the side edges of the cutters so as to maintain 15 the same in properly spaced relation when operative. The supporting member 3 is provided in its outer periphery with a dove-tailed slot 24 which extends longitudinally therein and is adapted to receive a 20 guide key 25. This key is adapted to project from the key slot in the supporting member for sliding engagement within a registering key slot 26 in the body socket 22. Owing to the provision of this guide 25 key, the supporting member will be guided during its upward movement in assembling the same within the body socket, whereby the recess 6 in the said body will be brought into proper registration with the body opening 5.

The body 1 is provided above the socket 2 with a longitudinally extending slot 27 which opens through the sides thereof and is adapted for the reception of a cross-head 28, which latter is vertically slidable therethrough and is connected medially in a detachable manner with the upper end of the plunger 19. A helical compression spring 29 is mounted upon the plunger between the lower wall of the body slot 27 and the cross-head. This spring is adapted normally to maintain the plunger in its uppermost operative position, wherein it renders the cutters operative. Upwardly projecting dogs 30 have their lower, reduced ends 31 pivotally mounted within terminal slots 32 in the cross-head, limiting shoulders 33 being provided upon these dogs at a short distance above the upper face of the cross-head for engagement therewith, to limit the swinging movement thereof to such an extent that the body portions of the dogs will not project outwardly past the outer periphery of the body 1 of the tool. These 45 dogs are adapted for movement through the longitudinal grooves 34 which are provided in the outer periphery of the body 1 in communication with the slot 27 and extending upwardly therefrom. An actuating lug 35 50 is formed upon the free end of each dog 30 and is adapted to project outwardly from the body 1 when the dog is in its uppermost, inoperative position. The body grooves 34 are deepened at their lower ends 55 to provide recesses 36, which are adapted to

receive the free ends of the dogs 30 when in their lowermost operative position, so that the lugs 35 may drop into the grooves and thus be unobstructing when the plunger is inoperative. The upper walls 37 of the groove 70 form shoulders for locking engagement with operative positions, wherein they are maintained by contact between the outer longitudinal edges of the lugs 35 and the inner periphery of a well casing through which the 75 tool may be passing. The upper end of each actuating lug 35 is beveled as at 38 for a purpose which will be described more fully hereinafter.

The operation of the device will now be described. Prior to lowering the tool through a well casing, such as is indicated by the numeral 39, the cross-head 28 is depressed into operative position against the action of the resetting spring 29 for the 80 plunger, until the free ends of the dogs 30 are engaged with the locking shoulders 37. The plunger will thus be depressed into its inoperative position so as to permit the outwardly flaring cutters to be collapsed, so 85 that they will not project past the outer periphery of the body. While the dogs 30 are maintained in operative position by pressing the actuating lugs inwardly, the tool as a whole may be inserted into the upper end 90 of the well casing, whose inner periphery will contact with the outer edges of the said lugs to maintain the dogs operative during the descent of the tool through the casing. As soon as the tool has emerged from the 95 lower end of the casing, the actuating lugs will be released, thus permitting the dogs to move outwardly and release the plunger, which latter will be thrust upwardly into 100 operative position by the action of its resetting spring. The expanding enlargement 21 and head 22 will thus operate to render the cutters operative and maintain the same rigidly in proper relation to the body 2 for 105 active use. When it is desired to withdraw the tool through the casing, its body is drawn upwardly, whereupon the beveled end faces 38 of the actuating lugs will become engaged with the lower end of the tube so as to thrust the dogs downwardly 110 to the limit of their movement, whereupon the said casing end will operate to thrust the lugs and consequently the free ends of the respective dogs inwardly into operative 115 engagement with the locking shoulders 37. This operation of the dogs will move the plunger downwardly into inoperative position releasing the cutters and permitting the same to collapse for free movement through 120 the casing. Owing to the manner in which the cutters are connected with the body of the tool, they may be removed readily for the purpose of sharpening or replacing the same by new cutters by merely removing 125 the pin 4 while the plunger is inoperative, 130

whereupon the supporting member may be withdrawn and one or more of the cutters may be detached therefrom.

What is claimed is:

5. 1. An under-reamer comprising an elongated body having a socket in its lower end, a plurality of cutters having their upper ends pivotally mounted within the body socket for radial swinging movement, the 70
10 said cutters being adapted to project laterally from the outer periphery of the body in operative position and being adapted to collapse into inoperative position, a longitudinally adjustable plunger mounted within 75
15 the body, an expanding head provided upon the lower end of said plunger for wedging engagement with the cutters when moved upwardly into operative position, yieldable means for normally maintaining the plunger 80
20 in its operative position, the body being provided with a longitudinal slot opening through its outer periphery and with a longitudinal groove in the said periphery in communication with the upper end of the
25 slot, a cross-head mounted fixedly upon the plunger for movement within the body slot, and an upwardly projecting dog pivotally mounted upon the outer end of the cross-head for movement within the said body 85
30 groove, the body being provided in the lower end of the said groove with a recess affording an inclined upper wall for locking engagement with the free end of the dog when the plunger is in its depressed, in- 90
35 operative position.
2. An under-reamer comprising an elongated body having a socket in its lower end, a plurality of cutters having their upper ends pivotally mounted within the body 95
40 socket for radial swinging movement, the said cutters being adapted to project laterally from the outer periphery of the body in operative position and being adapted to collapse into inoperative position, a longitudinally adjustable plunger mounted within 100
45 the body, an expanding head provided upon the lower end of said plunger for wedging engagement with the cutters when moved upwardly into operative position, yieldable means for normally maintaining the plunger in its operative position, the body being provided with a longitudinal slot opening through its outer periphery and with a longitudinal groove in the said periphery in communication with the upper end of the slot, a cross-head mounted fixedly upon the plunger for movement within the body slot, an upwardly projecting dog pivotally mounted upon the outer end of the cross-head for movement within the said body groove, the body being provided in the lower end of the said groove with a recess affording an inclined upper wall for locking engagement with the free end of the dog when the plunger is in its depressed, inoperative position, and an actuating lug formed upon the outer edge of the said dog and being adapted to project outwardly from the body when the dog is in its uppermost, inoperative position and to be contained within the body groove when the dog is operative, the upper face of the actuating lug being inclined longitudinally. 110
4. An under-reamer comprising an elongated body having a longitudinal socket in its lower end, the lower end portion of the socket being enlarged, a supporting member adapted to be mounted removably within the body socket with its lower end projecting into the enlarged portion thereof, a plurality of cutters pivotally connected with the lower end of the supporting member and being adapted to project through the lower end of the socket and laterally from the outer periphery of the body when operative, and means for securing the supporting member detachably within the body. 115
120
5. An under-reamer comprising an elongated body having a longitudinal socket in its lower end, the lower end portion of the socket being enlarged, a supporting member adapted to be mounted removably within the body socket with its lower end project- 125
130

- ing into the enlarged portion thereof, a plurality of cutters pivotally connected with the lower end of the supporting member and being adapted to project through the lower end of the socket and laterally from the outer periphery of the body when operative, the body and supporting member being provided with alining transverse openings, and a securing pin adapted to be mounted removably within said opening.
6. An under-reamer comprising an elongated body having a longitudinal socket in its lower end, the lower end portion of the socket being enlarged, a supporting member adapted to be mounted removably within the body socket with its lower end projecting into the enlarged portion thereof, a plurality of cutters pivotally connected with the lower end of the supporting member and being adapted to project through the lower end of the socket and laterally from the outer periphery of the body when operative, the body and supporting member being provided with alining transverse openings, a securing pin adapted to be mounted removably within said opening, the supporting member and the wall of the

body socket being provided with alining longitudinal slots, and a key mounted within the said slot.

7. An under-reamer comprising an elongated body having a longitudinal socket in its lower end, the lower end portion of the socket being enlarged, a supporting member adapted to be mounted removably within the body socket with its lower end projecting into the enlarged portion thereof, a plurality of radial pins provided upon the outer periphery of the supporting member at the lower end thereof, a plurality of cutters having radial openings in their upper ends loosely engageable with the pins of the supporting member, the said cutters being adapted to protrude from the body socket and to project laterally from the outer periphery of the body when operative, and adjustable means for securing the cutters in their expanded, operative positions.

In testimony whereof I affix my signature in presence of two witnesses.

FRANK A. HAUGH.
